(57) **CLAIM**

The ornamental design for a cosmetic applicator, as shown and described.

DESCRIPTION

FIG. 1 is a top perspective view of a cosmetic applicator, showing my new design;

FIG. 2 is a bottom perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front cross-section view thereof, taken along line 9-9 of FIG. 7; and,

FIG. 10 is a bottom perspective cross-section view thereof, taken along line 10-10 of FIG. 2.

The broken lines in the figures illustrate the portions of the design that form no part of the claimed design.
